UNITED STATES PATENT OFFICE.

HARRY J. GRUBER, OF NEW YORK, N. Y.

DESIGN FOR A LIGHTING FIXTURE.

Application filed August 17, 1928. Serial No. 27,855. Term of patent 7 years.

To all whom it may concern:

Be it known that I, HARRY J. GRUBER, a citizen of the United States, residing in the borough of Manhattan, city, county, and State of New York, have invented a new, original, and ornamental Design for a Lighting Fixture, of which the following is a specification, reference being had to the accompanying drawings, forming part thereof, wherein the single figure is a side view of a lighting fixture illustrating my design.

I claim:

The ornamental design for a lighting fixture, as shown.

HARRY J. GRUBER.
